Patented Sept. 21, 1976

241,580

ELASTIC DEFLATABLE AIR BAG FOR INHALATION SYSTEM OR THE LIKE

Robert A. Huddy, 1044 Balboa Drive,
Arcadia, Calif. 91006

Filed June 2, 1975, Ser. No. 582,784

Term of patent 14 years

Int. Cl. D29—02

U.S. Cl. D83—1 G

FIG. 1.

FIG. 3.

FIG. 2.

FIG. 4.

FIG. 1 is a front perspective view of an elastic deflatable air bag for inhalation system or the like showing my new design.

FIG. 2 is a front elevational view thereof.

FIG. 3 is a side elevational view thereof.

FIG. 4 is a rear elevational view thereof.

I claim:

The ornamental design for an elastic deflatable air bag for inhalation system or the like, substantially as shown.
